Patented Sept. 7, 1926.

UNITED STATES PATENT OFFICE.

JOHN E. SWEET, OF PITTSBURGH, PENNSYLVANIA, ASSIGNOR TO PITTSBURGH PLATE
GLASS COMPANY, A CORPORATION OF PENNSYLVANIA.

GATE FOR GLASS TANKS.

Application filed January 13, 1926. Serial No. 80,970.

The invention relates to a water cooled gate for shutting off the flow of glass from a glass tank, such as is used for the continuous formation of a ribbon of glass. The invention has for its principal object the provision of a gate of the type specified, which permits the application of the heat from the tank to the portion of the tank forward of the gate at the same time that it is applied at the back of the gate, and without withdrawing the gate from its position in the glass, thus permitting of a more gradual application of the heat to the clay slot member forward of the gate. With such gradual application of heat, the danger of injury to the slot member due to cracking is reduced. One embodiment of the invention is illustrated in the accompanying drawings, wherein:

Figure 1 is a vertical section through a glass tank with the invention applied thereto. And Figs. 2, 3 and 4 are detail views of the gate to which the invention particularly relates, Fig. 2 being a front elevation, Fig. 3 a plan view, and Fig. 4 a section on the line IV-IV of Fig. 2.

Referring to the drawings, 1 is the forward end of a glass melting tank containing a body of molten glass 2 and having at its end the removable wall 3 provided with the outlet slot 4. Forward of the slot 4 are a pair of rolls 5, 5 for forming the continuous ribbon of glass 6, which passes through a leer and is then cut into separate sheets.

Lying to the rear of the outlet slot 4 are the gates 7 and 8, the gate 7 being shown in its uppermost position, and the gate 8 in its lowermost position. The gate 7 is of refractory material supported from above by means of chains 9 connected to a crane. This gate is not ordinarily used, but in case of emergency or accident to the gate 8 it may be lowered so as to cut off the flow of glass to the outlet slot 4.

The gate 8 to which the invention particularly relates is also supported from above by means of chains 10 connected to a crane whereby the gate may be raised and lowered and moved laterally from its position above the tank. This gate consists of a bottom portion 11 adapted to be immersed in the glass and two side portions 12, 12 extending upward from the portion 11, the three parts

together constituting a U when viewed in front elevation (Fig. 2). This main portion of the gate is built up of boiler plate stayed at proper intervals by the bolts 13 which extend through from the plates on one side to those on the other.

Mounted above the bottom portion 11 and between the side portions 12, 12 is a second gate 14 also mounted for vertical movement by means of the chains 15 carried by the crane which supports the other gate members. The member 14 is also built up of boiler plate suitably stayed by bolts 16, and is guided in its vertical movement by means of the members 17 and 18, the members 17 being welded to the side members 12, 12 of the main portion of the gate, while the members 18 are welded to the gate member 14 and fit beneath the edges of the members 17.

The main portion of the gate is water cooled by means of an inlet pipe 19 through which water is supplied and by means of outlet pipes 20, such pipes being connected to flexible hose so as not to interfere with the raising and lowering of the gate. Similarly, the gate member 14 is cooled by means of a circulation of water through the inlet pipe 22 and the outlet pipe 23, such pipes also being connected to flexible hose for supplying and carrying away the water. In case sediment collects in the gate members, this may be loosened by means of the air pipes 24 and 25 having the horizontal portions 26 and 27 provided with outlet perforations along their lower sides.

In operation when it becomes necessary to remove the wall member 3, due to wear or corrosion around the slot 4, the gate is lowered into the glass, as indicated in Fig. 1, so that the glass in contact therewith is chilled and hardened. The rolls 5, 5 and 28 forward of the gate is broken away and removed. The new wall 3 is then put in position and also the rolls 5. The method of heating up the new wall preliminary to raising the gate has heretofore been to heat with burners through flues or openings 29 on opposite sides of the tank, but with this method it has been found very difficult, and practically impossible to get the front wall at a proper temperature to receive the glass when the gate was raised, and as a result, the front wall, and particularly the portion surround-

- ing the slot 4 was more or less injured due to cracking and spalling incident to the sudden application of heat and incident to the flow of the glass and the raising of the gate.
- 5 With the present operation involving the two part gate, the main portion of the gate is left in its lower position, so that the bottom end of the gate blocks any flow of glass when the small gate member 14 is raised.
- 10 In starting the operation with the new apparatus, the gate member 14 is first raised either in part or in whole, thus admitting heat from the tank through the opening and into the space between the gate and the wall
- 15 3. By leaving this small gate up, a proper period of time, the portion of the furnace to the front of the gate, including the wall 3 and the clay surrounding the outlet 4, are brought to a uniform temperature of such
- 20 high degree that when the glass is admitted to the front of the gate and the rolling operation started, there is no injury to the clay work. When the area to the front of the gate is properly heated through the opening provided by the lifting of the small gate, the main gate is lifted in the usual way, permitting the glass to flow gradually into the space at the front of the gate, thus placing the apparatus again on an operating basis.
- 25 30 What I claim is:—
1. The combination with a melting tank having an outlet opening at its forward end, of a water cooled metal gate member of U form mounted for vertical movement, and a movable water cooled section fitting in said gate member and mounted for vertical movement therein.
2. The combination with a melting tank having an outlet opening at its forward end, of a water cooled metal gate member of U form mounted for vertical movement, and a movable water cooled section fitting in said gate member and mounted for vertical movement therein. 40
3. The combination with a melting tank having an outlet opening at its forward end, of a water cooled metal gate member to the rear of such outlet opening having an opening therethrough and mounted for vertical movement, and a movable water cooled section closing said opening and mounted for vertical movement in said gate member. 45
- 35 4. The combination with a melting tank having an outlet opening at its forward end, of a water cooled metal gate member of U form mounted for vertical movement, and a movable water cooled section fitting in said gate member and mounted for vertical movement therein, the bottom portion of said gate member being arranged to lie with its upper edge above the level of the glass when said gate member is in its lowered or operative position. 60
- In testimony whereof, I have hereunto subscribed my name this 5th day of January, 1926.

JOHN E. SWEET.
